UNITED STATES PATENT OFFICE.

JAMES LITTLE, OF EVANSVILLE, INDIANA.

COTTON-PRESS.

SPECIFICATION forming part of Letters Patent No. 553,924, dated February 4, 1896.

Application filed July 27, 1894. Serial No. 518,739. (No model.)

To all whom it may concern:

Be it known that I, JAMES LITTLE, a citizen of the United States, residing at Evansville, in the county of Vanderburg and State of Indiana, have invented a new and useful Cotton-Press, of which the following is a specification.

My invention relates to improvements in cotton-compresses, and it has for its object 10 to provide a simple, efficient, and durable device for compressing cotton in flat or "layer" bales, the table or support for the bale being mounted for automatic adjustment upon a reciprocating carrier, from which is derived 15 the power for operating the compressing-rolls.

Further objects and advantages of the invention will appear in the following description, and the novel features thereof will be 20 particularly pointed out in the appended claims.

In the drawings, Figure 1 is a perspective view of a press embodying my invention. Fig. 2 is a central longitudinal section of the 25 same. Fig. 3 is a detail view of one of the clutches for connecting the power-gears to the rolls. Fig. 4 is a transverse section taken parallel with the axis of one of the compressing-rolls.

Similar numerals of reference indicate 30 corresponding parts in all the figures of the drawings.

1 designates the supporting-framework, which is substantially rectangular in form, 35 and 2 represents a reciprocating carrier fitted slidably therein and having a bottom plate 3 and parallel side plates 4, which are equal in height to the interior of the framework. This carrier is provided at its center with a box 5, in which is slidably fitted for vertical movement the stem 6 of the table or support 8, said table or support being equal in width to the interval between the inner surfaces of the side plates of the carrier, whereby it is 40 guided by said plates. The box 5 is provided with a movable side plate 9, held in place and secured to the body portion of the box by means of set-screws 19, and this plate 9 acts in the capacity of a pressure or friction plate,

which may be adjusted by means of the said 50 set-screws to press with any desired degree of force against the stem 6 of the table or support. It is by this frictional contact of the stem of the table or support with the surfaces of the box or guide in which it is fitted 55 that the table or support is allowed to recede as the bale increases in size, and yet offers sufficient resistance to the force by which it is caused to recede that the desired compression of the bale is attained. 60

The above-described means for controlling the resistance of the table to the re-pressing force of the compressing-rolls provides for an even resistance throughout the movement of the table and avoids a varying resistance as 65 the table recedes. Furthermore, the means for controlling the resistance of the table are compactly arranged within the carrier and are unaffected by the reciprocation of the carrier, and no special construction of framework is necessary when this arrangement of tension is employed. It is obvious that 70 weights connected to the receding table or support to control the compression of a bale cannot be arranged in the compact form possible with the above-described device, and in addition thereto they increase the weight of the carrier without reference to means which must be employed for preventing the weights from swinging during the reciprocation of the 75 carrier. The improved means for controlling the resistance of the table do not add materially to the weight of the carrier and they occupy space which cannot otherwise be utilized, and in addition to these advantages it 80 will be obvious that the device may be constructed at a small cost, and new friction-plates, necessitated by wear after prolonged use, may be applied with a small outlay. 85

Mounted rotatably in suitable bearings in 90 the side walls of the framework are the spindles 10 of the pressure-rolls 11, said spindles being extended beyond one side of the framework and being provided with intermeshing spur-gears 12, whereby motion is communicated from either roll to the other, and mounted loosely upon said spindles between the ends of the rolls and adjacent walls of the frame- 95

work are the power-gears 13, which are connected to the spindles by means of clutches 14. The clutches are so arranged as to engage and communicate motion to the spindles 5 of the rolls only when turned inward, or in the direction indicated by the arrows in Fig. 2, and to slip idly when turned in the opposite direction. The carrier is provided at the upper edges of its side plates with racks 15, 10 which mesh, respectively, with said power-gears.

Therefore when the carrier is reciprocated by means provided for that purpose and through the bar 16 which is connected to said 15 carrier the motion is communicated through the racks to the power-gears, whereby the latter are turned alternately in opposite directions; but as the power-gears communicate motion to the rolls only when rotated inward 20 or in one direction, and as the rolls are geared together so as to turn simultaneously in opposite directions, it will be seen that the rolls turn continuously in one direction, and thus draw the cotton downward between their contiguous 25 inner sides and fold or lap it regularly upon the upper surface of the table or support, as shown in Fig. 2. The cotton is conveyed from the cotton-gin (not shown) by means of an endless apron 17 or similar device. (Shown in Fig. 2.)

Arranged upon opposite sides of the compressing-rolls and parallel therewith are the auxiliary pressing-rolls 18, which are arranged with their lower sides in the same horizontal 35 plane with the lower sides of the compressing-rolls 11, and which bear continuously upon the upper surface of the bale as it is formed. These auxiliary rolls prevent the displacement 40 by engaging the latter as it is fed between the compressing-rolls and holding it in position during the movements of the carrier.

It will be understood that various changes in the form, proportion, and minor details of 45 construction may be resorted to without departing from the spirit or sacrificing any of the advantages of the invention.

Having described my invention, what I claim is—

50 1. In a cotton-press, the combination with feeding and compressing rolls mounted in fixed bearings, and means for operating the same, of a table or support for the bale, mounted for movement toward and from the plane of the compressing-rolls and adapted to be moved from the same by the pressure applied to a bale during compression, said pressure being caused by the successive introduction of layers between the compressing-rolls 55 and the contiguous side of the partially-formed bale, and an adjustable friction device arranged in contact with the table or support and capable of movement toward and from the path of movement thereof to vary 60 the resistance offered by the table to move-

ment from the compressing-rolls, and thereby vary the amount of compression of the bale, substantially as specified.

2. In a cotton-compress, the combination with a supporting-framework, a reciprocatory carrier mounted therein, feeding and compressing rolls mounted in bearings on the framework and means for operating the same, of a table or support mounted upon and movable with said carrier, and adjustable means 75 arranged in frictional contact with the table or support, to resist the depression of the same, substantially as specified.

3. In a cotton-compress, the combination with a supporting-framework, of a reciprocatory carrier mounted therein and having parallel side walls supporting parallel racks, feeding and compressing rolls mounted in bearings on the framework, means for communicating motion from the racks to the compressing-rolls, a table or support mounted for reciprocation between the planes of and guided by the side walls of the carrier and adapted to move toward and from the plane of the compressing-rolls, an adjustable part 85 or member in frictional contact with the table and adapted to be moved toward and from the path of movement thereof, and means for adjusting said part or member to vary the resistance offered by the table or support to 90 the expansion of the bale carried thereby, substantially as specified.

4. In a cotton-compress, the combination with a supporting-framework, a reciprocatory carrier, and feeding and compressing rolls 100 and means for operating the same, of a table or support mounted upon the carrier and having a stem fitting slidably in a guide or box thereon, a pressure or friction plate in contact with said stem of the table, and means 105 for adjusting said plate to vary its pressure upon the stem of the table, substantially as specified.

5. In a cotton-compress, the combination with a supporting-framework, a reciprocatory 110 carrier, and feeding and compressing rolls and means for operating the same, of a table or support provided with a stem, a guide or box on said carrier for the reception of said stem of the table, a movable or adjustable 115 plate forming one side of said guide or box, and means, consisting of set-screws, for varying the pressure of said plate upon the stem of the table, whereby the resistance offered to the repression of the table is regulated, 120 substantially as specified.

6. In a cotton-compress, the combination of a framework, a reciprocatory carrier slidably mounted therein, a table or support mounted upon the carrier, compressing-rolls 125 mounted in bearings in the framework and provided with intermeshing spur-gears, power-gears mounted respectively upon the spindles of the compressing-rolls, clutches connecting said power-gears to the rolls, racks 130

carried by the sliding carrier and meshing respectively with the power-gears, and auxiliary rolls arranged upon opposite sides of the compressing-rolls with their lower sides in
5 the plane of the lower sides of the compressing-rolls, and adapted to traverse the surface of the bale, substantially as specified.

In testimony that I claim the foregoing as my own I have hereto affixed my signature in the presence of two witnesses.

JAMES LITTLE.
